UNITED STATES PATENT OFFICE

HUBERT H. FLIEGEL, OF MERRICK, NEW YORK

HATCH CONSTRUCTION FOR UPPER DECKS

Application filed May 5, 1931. Serial No. 535,261.

This invention relates to hatches for marine vessels, and has more particular reference to an improved top deck hatch construction which is applicable to passenger, general cargo or other types of vessels where it is desirable to render the hatchway watertight.

The outstanding object of the present invention is to provide a top or shelter deck hatch, in which the cover or covers therefor may be handled with greater facility and more expeditiously by a lesser number of men than is now possible, and in which the covers when removed are capable of being stowed, so as to offer a minimum of interference with the use of the deck space and to the loading or unloading of the cargo.

The invention further resides in a hatch for top or shelter decks, which is preferably of steel construction and so fashioned as to obtain a self sealing watertight relation between the covers and the coaming to obviate the necessity of employing tarpaulins.

The invention further embodies means for mounting the hatch covers for rolling support upon the deck and for limited raising and lowering movement to respectively effect the clearing of the coaming when uncovering the hatchway and the seating of the covers on the coaming when closing the hatchway.

As a further object, the invention embodies, in certain instances, means for permitting of the swinging and supporting of certain of the hatch covers into a vertical out-of-the-way position.

Another object in view is to provide means for drawing and retaining the hatch covers into intimate water-tight relation to the coaming and to each other, in order to insure against accidental displacement thereof due to heavy weather or leakage through the hatchways.

A still further aim is to provide a hatch construction in which the arrangement and manner of supporting the hatch covers admit of partial and selective uncovering of various portions or areas of each hatchway when it is undesirable or unnecessary to completely uncover the hatchways.

The invention further aims to generally

improve a top or shelter deck hatch structure without unduly complicating the same and providing a hatch which is sufficiently strong and durable to last throughout the length of life of the vessel.

With the above recited and other objects in view, reference is had to the following description and accompanying drawings, in which there is exhibited one example or embodiment of the invention, while the claims define the actual scope of the same.

In the drawings:

Figure 1 is a diagrammatic side view of a vessel equipped with top or shelter deck hatches constructed in accordance with the invention.

Figure 2 is a fragmentary plan view thereof.

Figure 3 is an enlarged longitudinal sectional view showing the hatchway opened and with the covers in their stowed positions.

Figure 4 is a plan view on a larger scale illustrating the hatch covers in closed sealed relation to the hatchway.

Figure 5 is a fragmentary transverse sectional view taken approximately on the line indicated at 5-5 in Figure 4.

Figure 6 is a further enlarged fragmentary sectional view through the connected meeting edges of the hatch covers, the same being taken approximately on the line indicated at 6-6 in Figure 4.

Figure 7 is a further enlarged sectional view taken approximately on the line indicated at 7-7 of Figure 4, illustrating the hatch cover in its sealed watertight condition and particularly illustrating the clamping down means carried by the cover supporting means.

Figure 8 is a similar view illustrating said clamping down means released and the hatch cover raised to clear the coaming.

Referring to the drawings by characters of reference, A designates the hull of a vessel provided with the usual forecastle head B, top deck C, Samson posts D, from which is supported the tackle for handling the hatch covers and cargo. Certain of the winches E are supported on elevated platforms F for a purpose which will be hereinafter set forth.

In the illustration disclosed in Figures 1 and 2, the two forward hatches G and H are disclosed in order to illustrate several applications of the present invention, which will be later developed. The hatchways include the usual coaming 10, which in the present instance is preferably of steel construction, having a grooved or channeled upper marginal edge 11 which is designed to receive a hemp packing 12 which is laid into the groove or channel just prior to the closing of the hatch and which is removed and properly stowed immediately upon the opening of the hatch.

Each hatch may include one or more covers, depending upon its size, but in the present instance, the two forward hatches illustrated each include two sections, namely, a long section 13 and a short section 14, both of which are of a width to cover the entire width of the hatchway and of a length to combine to cover the entire length of the hatchway. The foremost hatch G as illustrated, and commonly termed No. 1 hatch, is disposed immediately in rear of the forecastle head B, which forecastle head affords a convenient means for the reception and stowage of a hatch cover by constructing the same to form a stowage space indicated by the reference character I. It thus follows that in the foremost or No. 1 hatch G, the longer hatch cover 13 is disposed forwardly for shifting movement into the stowage compartment I to uncover the hatchway. The shorter cover section 14 is disposed rearwardly for rearward movement to uncover the hatchway and is designed to be received and stowed under the elevated winch platform F. No. 2 hatchway, indicated by the reference character H, has the shorter cover section 13 disposed forwardly and the longer cover section 14 disposed rearwardly, and the forward shorter cover section 13 is designed to be shifted forwardly to uncover the hatch and for stowage under the elevated winch platform F which is directly in front of the No. 2 hatch. In this instance, the longer rear hatch cover section 14 is designed to be moved by suitable tackle rearwardly and upwardly to the dotted line position illustrated in Figure 1 and to the full line position illustrated in Figure 3.

The hatch cover sections 13 and 14 are substantially of identical construction except for their difference in length, and each includes a main body portion 15 having upstanding opposite side walls 16 and upstanding outer end walls 17, which walls are provided with outwardly projecting horizontal flanges 18. The main or body portions 15 are transversely braced by angle braces 19a applied to the upper surfaces thereof and extending between the upstanding side walls 16. In order to drain water from the upper surface of the hatch covers, scupper openings 19 are provided at the juncture of the side and end walls with the main body portion 15. The under

side of the hatch cover sections is provided with suitable depending positioning means 20, which means is designed to snugly fit within the upper end of the hatchway coaming 10, to assist in preventing accidental shifting of the hatch covers and to properly gauge the positioning of the same on the coaming.

In order to provide means for clamping down the hatch cover sections on the coaming and to insure a watertight relation of the covers with the packing 12, interengageable clamping means is provided on the covers and coaming, which means as illustrated consists of a plurality of clamping rods 21 extending through the upwardly offset marginal flanges 18 and depending therefrom through sleeves 22 carried by the flanges with the lower hooked terminals 23 designed to engage within a suitable seat 24 formed on the sides of the coaming. The upper threaded ends 25 of the rods receive thereover nuts 26 for drawing upwardly on the clamping rods 21. The seat 24, as illustrated, is in the nature of an inverted channel strip, although this is merely illustrative of varying equivalent means for performing this function. In order to connect the meeting edges of the sections 13 and 14 and to obtain a watertight relation therebetween, said meeting edges are provided with upstanding flanges 28 and 29 respectively, which flanges may preferably be formed as part of an angle strip, the base flanges 30 and 31 of which are riveted or otherwise attached to the cover sections. One of the cover sections is formed on its under side with a lap plate 32 which projects from the meeting edge and is designed to underlie the meeting edge of the other cover section. A plurality of swiveled rotary stud bolts 33 projects from the meeting edge flange 29 for engagement within the threaded openings 34 of the other meeting edge flange 28, and said bolts are provided with suitable manipulating heads 35 with which ratchet wrenches or convenient means are adapted to be engaged for turning the same. Suitable packing strips 36 and 37 are positioned between the flanges 28 and 29 prior to the drawing of the cover sections together, and said packings are impinged between the flanges to obtain a watertight joint.

The hatch cover sections are mounted and supported from the deck for rolling movement longitudinally with respect to the hatchways by means of flanged wheels 40 which are journaled in the forked feet 41, which feet are in turn carried by legs 42 which depend from the side flanges 18 and are rigidly covered by the hatch cover sections. The flanged rollers roll upon a track consisting of a pair of rails 43 secured to the deck on opposite sides of the hatchway coaming. The upper end of each foot slidably receives in the recesses 44 at its upper end, the

furcations 45 of the bifurcated lower end of the leg 42, whereby the legs and hatch cover sections may move vertically with respect to the feet. In order to effect vertical movements of the hatch cover sections and legs 42, a jackscrew 46 extends vertically through each leg and is provided with a manipulating wheel or head 47 at its upper end. The jackscrews are swiveled for rotation in bearings 48 which are carried by the hatch cover sections, and said jackscrews are held against relative axial movement with respect to the bearings and legs while permitted to rotate. A non-rotary nut 49 is supported between the leg furcations 45 for longitudinal movement and threadedly receives the jackscrew, whereby vertical motion upwardly and downwardly is imparted thereto by turning of the jackscrew in opposite directions. It is apparent that upon downward movement of the nut, the same will contact with the upper end of the foot 41, to effect upward movement of the legs 42 and hatch cover sections, and, conversely, upon upward movement of the nut, the legs and hatch cover sections are lowered. In order to effect the clamping down of the hatch cover sections at the points where the supporting legs occur, each foot is provided with a pair of rail gripping tongs 50, the cooperating jaws 51 at the lower ends of which are designed to clamp under the rail head, and the upper free ends 52 of which tongs are connected by links 53 to the nut 49. It thus follows that as the nut is moved upwardly to lower the hatch cover sections, a continued upward movement of the nut will cause the links 53 to exert a pull on the jaw ends for swinging the tong jaws 51 to a gripping position under the rail head, and further continued upward movement will cause the drawing down of the hatch cover section against the packing at the upper edge of the coaming. Conversely, a downward movement of the nut will through the links initially swing the jaws 51 of the tongs to a released position prior to the engagement of the nut with the upper end of the feet, to raise the hatch cover sections. In practice, it is obvious that the hatch cover sections are raised sufficiently to clear the positioning means 20 from the upper edge of the coaming and packing, after which the hatch covers are free to be rolled to an uncovered relation to the hatchway. In some instances, where it is undesirable to uncover the complete hatchway area, the hatchway cover section clamping means are released without disconnecting the meeting edges of the hatch covers from each other, and both sections may be moved in unison forwardly or rearwardly to uncover a portion of the hatchway area. In other instances, one hatch cover section may be moved without unclamping or moving the other hatch cover section.

In the hatchways, such as No. 2 hatch,

where there is not sufficient room to roll the hatch cover to a position to entirely uncover the hatchway, it is necessary to swing the angle hatch cover to an upright out-of-the-way stowed position. In this instance, the rail ends 60 are upturned and disposed vertically and the corresponding end of the hatch cover section is provided with rollers 61 which are designed to coact with the vertically disposed upturned ends 60, and the tackle on the Samson post D is employed for swinging the opposite end of the hatch cover upwardly until the cover assumes the vertical position illustrated in Figure 3, it being understood that the roller 61 guides the lower end of the hatch cover downwardly, where it is maintained between the rail ends and upstanding bars 62 which are attached to the deck between the track rails and in spaced relation to the upturned rail ends 60. This defines, in effect, a pocket for the reception of the lower edge of the cover. Hatch G or No. 1 hatch may be fully opened by moving the forward angle hatch cover 13 forwardly under the forecastle head B into the stowage space I and rolling the rear shorter hatch cover 14 rearwardly under the elevated winch platform F. Hatch No. 2 or hatch H may be fully opened by moving the shorter forward hatch cover section 13 forwardly under the elevated winch platform F and rolling the rear longer hatch cover rearwardly and swinging the same upwardly to an upright position. As previously set forth, the same principle applies to a hatch which employs only a single hatch cover, in which instance said cover will be of a proper size to completely cover the entire hatchway.

From the foregoing, it will thus be seen that a top or shelter deck hatch has been devised which is constructed of steel and is self sealing to avoid the necessity of the use of tar-paulins and the expense and inconvenience incident thereto, and in which the hatch covers are capable of being more expeditiously handled by a smaller crew, and which when not in active use are stowed or positioned so as to offer practically no interference with the deck space or the loading or unloading of the cargo. It is also apparent that hatches constructed in this manner will accommodate cargo elements of great length, in that the hatch covers when opened do not interfere with the loading of the cargo or its removal from the holds. It will be further noted that due to its rugged construction, the hatchway will practically last throughout the length of life of the vessel and will require little, if any, repairing.

While there has been illustrated and described a preferred embodiment of the invention, no limitation is intended to the precise structural details, as it is to be understood that variations and modifications which

properly fall within the scope of the claims may be resorted to when desired.

What is claimed is:

1. A top deck hatch including in combination a hatchway coaming having a packing at its upper marginal edge, a hatch cover adapted to seat upon the packed upper edge of the coaming and having depending means for engagement within the coaming, and means on the cover for supporting the same from the deck for shifting movement to covering and uncovering relation with respect to the hatchway, said supporting means including means for respectively raising the hatch cover to disengage said depending means from the coaming, and for lowering and drawing the hatch cover down into watertight relation to the packed upper edge of the coaming, with said depending means engaging within the coaming.
2. The combination with a top deck formed with a hatchway including a coaming, of a covering therefor including a pair of mating sections adapted to seat upon the packed upper edge of the coaming, means for independently supporting said sections from the deck for relative movement with respect to the hatchway and with respect to each other, interengageable means at the meeting ends of said sections for clamping a packing therebetween to form a water-tight joint, said latter means comprising a lap plate on the under side of and extending from the meeting end of one section and adapted to underlie the other section, a pair of upstanding flanges at the meeting ends of said sections, and means carried by one flange and engaging the other for drawing the sections together to clamp a packing therebetween.
3. The combination with a top deck formed with a hatchway including a coaming having a packing at its upper edge, of a covering therefor including a pair of mating sections adapted to seat upon the packed upper edge of the coaming, interengageable upstanding and underlapping means at the meeting ends of said sections for receiving and clamping a packing therebetween to form a water-tight joint, means for independently supporting said sections from the deck for relative movement with respect to the hatch and with respect to each other, said latter means including mechanism for raising, lowering and drawing the hatch sections into watertight relation with the coaming.
4. In a top deck hatch construction, a hatchway coaming, a hatch cover, wheeled supports depending from the opposite sides of the cover, a track on the deck including a pair of parallel rails disposed on opposite sides of the coaming and upon which the hatch cover is adapted to be moved to and from its covering relation to the coaming and means constituting a part of said supports for gripping said rails and drawing and

clamping the hatch cover down into engagement with the coaming.

5. A top deck hatch construction including a hatchway coaming having a packing at its upper edge, a hatch cover, means for supporting said cover from the deck for fore and aft rolling movement to and from a superposed relation to the hatchway and a common means constituting a part of the supporting means for effecting the raising and lowering of the hatch cover and for drawing the hatch cover when lowered into flat seating contact with the coaming packing.

6. In a top deck hatch construction, a hatchway including a coaming, a pair of hatch cover sections, means for independently supporting said sections from the deck for fore and aft rolling movement to and from a superposed relation to the coaming and for elevating and lowering and clamping down said sections on the coaming and interengageable means at the meeting edges of the sections for securing the same together in watertight relation.

7. In a top deck hatch construction, a hatchway coaming having a packing at its upper edge, a hatch cover, interengaging means on the hatch cover and coaming for clamping down the cover against the packed upper edge and means for supporting the hatch cover from the deck for shifting movement to and from its covering relation, said latter means including additional means for clamping down the cover against the packed upper edge of the coaming.

8. In a top deck hatch construction, a hatchway coaming having a packing at its upper edge, a hatch cover, vertically movable clamps depending from the margins of the hatch cover having hooked lower ends, seats on the coaming with which said hooked ends are engageable for clamping down the cover against the packed upper edge of the coaming and means for supporting the hatch cover from the deck for shifting movement to and from its covering relation, said latter means including auxiliary means for effecting the clamping down of the cover against the packed upper edge of the coaming.

9. In a top deck hatch construction, a hatchway coaming having a packing at its upper edge, a hatch cover, vertically movable clamps depending from the margins of the hatch cover having hooked lower ends, seats on the coaming with which said hooked ends are engageable for clamping down the cover against the packed upper edge of the coaming and means for supporting the hatch cover from the deck for shifting movement to and from its covering relation, said latter means including rigid brackets depending from opposite sides of the cover, flanged wheels carried by the lower extremities of the brackets and rails on the deck disposed on opposite sides of the coaming and upon

which the wheels roll, and devices forming a part of said latter means engageable with the rails for gripping the same and clamping down the cover against the packed upper edge 5 of the coaming.

10. In a top deck hatch construction, a hatchway coaming having a packing at its upper edge, a hatch cover, interengaging means on the hatch cover and coaming for 10 clamping down the cover against the packed upper edge and means for supporting the hatch cover from the deck including rigid brackets depending from opposite sides of the cover, flanged wheels carried by the lower 15 extremities of the brackets and rails on the deck disposed on opposite sides of the coaming and upon which the wheels roll, said brackets being adjustable in length to raise and lower the hatch cover and means oper- 20 able upon lowering of the hatch cover engageable with the rails for effecting an auxiliary clamping down of the hatch cover.

11. In a top deck hatch, a hatchway coaming having a packing at its upper edge, a 25 hatch cover adapted for watertight seating on the packed upper edge of the coaming and means for supporting the hatch cover from the deck for rolling movement to and from its covering relation relative to the 30 coaming, said means including track rails secured to the deck and extending along opposite sides of the coaming, depending legs on opposite sides of the hatch cover, feet at the lower ends of the legs, with which the 35 legs are connected for vertical movement, track engaging wheels journaled in the feet, jack means on each leg including a vertically movable nut operable upon upward movement to lower the hatch cover onto the coam- 40 ing and operable upon downward movement to engage the foot for raising the said cover with respect to the coaming.

12. In a top deck hatch, a hatchway coaming having a packing at its upper edge, a 45 hatch cover adapted for watertight seating on the packed upper edge of the coaming and means for supporting the hatch cover from the deck for rolling movement to and from its covering relation relative to the coaming, 50 said means including track rails secured to the deck and extending along opposite sides of the coaming, depending legs on opposite sides of the hatch cover, feet at the lower ends of the legs, with which the legs are con- 55 nected for vertical movement, track engag- ing wheels journaled in the feet, jack means on each leg including a vertically movable nut operable upon upward movement to lower the hatch cover onto the coaming and oper- 60 able upon downward movement to engage the foot for raising the said cover with respect to the coaming and rail gripping means carried by each foot operable by and upon upward movement of the nut after the cover 65 is lowered into contact with the coaming to

exert a drawing down of the cover into water-tight relation with the packing.

13. In a top deck hatch, a hatchway coaming having a packing at its upper edge, a hatch cover adapted for watertight seating 70 on the packed upper edge of the coaming and means for supporting the hatch cover from the deck for rolling movement to and from its covering relation relative to the coaming, said means including track rails 75 secured to the deck and extending along opposite sides of the coaming, depending legs on opposite sides of the hatch cover, feet at the lower ends of the legs, with which the legs are connected for vertical movement, 80 track engaging wheels journaled in the feet, jack means on each leg including a vertically movable nut operable upon upward movement to lower the hatch cover onto the coaming and operable upon downward movement 85 to engage the foot for raising the said cover with respect to the coaming, rail gripping means carried by each foot operable by and upon upward movement of the nut after the cover is lowered into contact with the 90 coaming to exert a drawing down of the cover into water-tight relation with the packing and an auxiliary cover clamping means pro- 95 vided respectively on the cover and coaming.

14. In a top deck hatch, a hatchway coaming, a track on the deck including parallel rails extending on opposite sides of the coaming, feet having wheels journaled therein for rolling engagement with the track rails, a hatch cover having depending legs at its 100 opposite sides and having vertical guided connection at the lower ends with the feet, a screw extending downwardly with respect to and swiveled to each leg, a non-rotary nut engaged by the screw, guided for vertical 105 movement by the leg and adapted upon downward movement to engage with the upper end of the foot to raise the hatch cover with respect to the coaming and adapted upon upward movement to lower the hatch cover onto the coaming and tongs carried by each foot operable by and upon upward movement of the nut, to engage the rails and draw the hatch cover into watertight contact 110 with the coaming.

15. In a hatch construction, a hatchway coaming, a track including parallel rails ex- 115 tends along opposite sides of the coaming and having upturned vertical ends disposed beyond the coaming, a hatch cover having 120 depending legs adjustable in length and pro- vided with track engaging wheels at the lower ends, rollers supported from and pro- truding beyond an end of the hatch cover and disposed adjacent the upper portion of 125 said cover for engaging with the upturned rail ends to guide downwardly the end of the hatch cover having the end rollers en- gaged with the upturned rail ends and for facilitating the upward swinging movement 130

of the other end of the hatch cover to a vertically stowed position parallel to the upturned rail ends.

16. In a hatch construction, a hatchway 5 coaming, a track including parallel rails extending along opposite sides of the coaming and having upturned vertical ends disposed beyond the coaming, a hatch cover having depending legs adjustable in length and provided with track engaging wheels at the lower ends, rollers at the ends of the hatch cover to engage with the upturned rail ends for guiding the cover for swinging movement to and from a vertical stowed position and 15 means spaced from and within the upturned rail ends to cooperate with the rail ends for holding the hatch cover in its vertical stowed position.
